SCREW DRIVER

Gustav Prall, New York, N. Y.

Application December 9, 1942, Serial No. 468,338

1 Claim. (Cl. 145—61)

This invention relates to screw drivers and refers more particularly to handles thereof.

An object of the present invention is the provision of a screw driver having a revolving portion which is connected with a stationary portion in a firm, secure and effective manner.

Another object is the provision of a screw driver handle which may be conveniently made of any suitable composition material and which includes a portion receiving the pressure of the hand while the remaining portion of the screw driver rotates for the purpose of removing or inserting a screw.

Other objects of the present invention will become apparent in the course of the following specification.

In accomplishing the objects of the present invention, it was found desirable to provide a screw driver having a handle consisting of two main portions. One of these portions is firmly connected with a blade of the screw driver. The other portion rotates in relation to the first mentioned portion and is connected therewith by a stationary rivet, screw, or similar member. A bearing which may consist of a plate, a roller or the like is interposed between the two parts of the handle to facilitate rotation and diminish friction between the two parts.

The invention will appear more clearly from the following detailed description when taken in connection with the accompanying drawing, showing, by way of example, preferred embodiments of the inventive idea.

In the drawing:

Figure 1 shows a screw driver in side elevation.

Figure 2 is a section along the line 2—2 on an enlarged scale.

Figure 3 is a top view of the screw driver shown in Fig. 1.

Figure 4 shows a somewhat differently constructed screw driver in side elevation.

Figure 5 is a section along the line 5—5 on an enlarged scale.

Figure 6 is a side view illustrating the rotary handle portion of the screw driver shown in Fig. 4.

Figure 7 is a top view of the stationary part of the handle of the screw driver shown in Fig. 4.

The screw driver shown in Figures 1, 2 and 3 of the drawing, includes a blade 8, having an operative lower end 9, and an upper end 10, which is firmly embedded in the stationary handle portion 11. The handle portion may be cylindrical in form and may include one or more

annular grooved portions 12, as well as transverse ribs for facilitating the grasping of the handle.

The top portion 13 of the handle is rotatable in relation to the portion 11. The portion 13 is mounted upon a pivot or rivet 14, which is inserted with a pressed fit into the handle portion 11 and is firmly embedded therein. Preferably the pivot 14 is located in the center of the handle portion 11 and at the top thereof. The conical head 15 of the pivot 14 is located within a recess 16 formed in the handle portion 13. The portion 13 may be separated from the portion 11 by a groove or recess 17.

The recess 16 is covered by a plate 18 which is firmly embedded in the handle portion 13 and is rotatable therewith. Due to this arrangement the finger of the hand of the user does not come in contact with the pivot 14.

A plate 19 is interposed between the handle portions 11 and 13. The plate 19 has an opening through which the pivot 14 extends, and it is made of any suitable material which will diminish friction between a rotary and a stationary surface.

In operation, the user engages a screw with the end 9 of the screw driver and at the same time presses against the handle portion 13, this pressure extending in the longitudinal direction of the screw driver. With the other hand the user turns the handle portion 11 and the blade 8 connected therewith. The pivot 14 will rotate along with the handle portion 11 but the plate 18, and the handle portion 13 will remain stationary serving as a convenient support for the hand, the pressure of which is transmitted to the blade 8.

It is apparent that the described screw driver head is inexpensive to manufacture and may be conveniently fitted to any existing screw driver.

The handling and the manipulation of a screw driver are greatly facilitated by the described construction.

The screw driver shown in Figures 4 to 7 comprises a blade 20, a handle portion 21, and another handle portion 22. The main handle portion 21 may have the form of a ribbed cylinder provided with a recessed part 23 and carrying one end of the blade 20 which is firmly embedded therein.

As shown in Figure 5, the upper end of the handle portion 21 contains an annular recess 24 which encloses a central support 25 and which is enclosed by walls 26. The support 25 and the wall 26 are integral with the handle portion 21 and may be made of wood, Lucite or some other suit-

able material. The support 25 has a central curved supporting surface 27, carrying a ball 28.

The ball 28 constitutes a bearing separating the handle portion 22 from the handle portion 21.

As shown in Figures 5 and 6, the handle portion 22 has the form of a cup-shaped body which fits into the recess 24 and encloses the support 25. The body 22 has a curved or rounded portion 38 which extends outside of the walls 26 and serves as a rest for the fingers or the hand of the user. The body 22 also has cylindrical walls 30 and 31 separated by an annular groove 29. A ring 37 is mounted upon the support 25 and serves as a race for the body 22 which is somewhat spaced from the walls 26. Due to this arrangement, friction is reduced to a considerable extent.

The walls 26 are provided with a threaded opening 32, containing a screw 33. The inner end of the screw 33, projects into the recess 24 and is situated within the groove 29 of the rotary handle portion 22. To facilitate engagement with the screw 33, the underlying surface 34 of the groove 29 may extend at right angles of the longitudinal axis, while the opposite surface 35 may be oblique or inclined in relation to this axis.

The screw 33 prevents the handle portion 22

from falling out while the ball bearing 28 facilitates the rotary motion between the handle parts 21 and 22.

What is claimed is:

5 A screw driver head, comprising a substantially cylindrical head portion having a screw driving blade connected therewith, and the free end of said head portion having an annular recess formed therein, providing an outer annular wall 10 and an integral central cylindrical support, a second cylindrical head portion of smaller diameter than the first head portion having a central recess formed therein to accommodate said support, said second head portion being rotatable located in said annular recess and slightly extending above the free end of said first head portion, said second head portion having an annular peripheral groove formed therein, a set screw carried by the outer annular wall of the 20 first head portion and projecting into said annular groove holding the second head portion in rotatable relation to the first head portion, a ball carried by said support and engaging the bottom in the recess of said second head portion, 25 and a ring surrounding said support and providing a race for said second head portion.
